CLAIM

We claim the ornamental design for a go kart, as shown and described.

DESCRIPTION

FIG. 1 is a top front perspective view of the go kart according to the new design.

FIG. 2 is a bottom front perspective view of the go kart shown in FIG. 1.

FIG. 3 is a top rear perspective view of the go kart shown in FIG. 1.

FIG. 4 is a bottom rear perspective view of the go kart shown in FIG. 1.

FIG. 5 is a front elevation view of the go kart shown in FIG. 1.

FIG. 6 is a rear elevation view of the go kart shown in FIG. 1.

FIG. 7 is a left side elevation view of the go kart shown in FIG. 1.

FIG. 8 is a right side elevation view of the go kart shown in FIG. 1.

FIG. 9 is a top plan view of the go kart shown in FIG. 1; and, FIG. 10 is a bottom plan view of the go kart shown in FIG. 1.

The broken lines in the drawings illustrate portions of the go kart that form no part of the claimed design.

1 Claim, 10 Drawing Sheets
